MANIPULATING DEVICE

Andrew Pfeiffer, Old Lyme, Conn.

Application December 26, 1957, Serial No. 705,227

13 Claims. (Cl. 74—507)

The present invention relates generally to an improved manipulating device, and it relates more particularly to an improved device for linearly, longitudinally advancing and retracting a tool for accurately measured distances in the absence of any significant torque, wobble, backlash or lateral movement.

There are many applications which require the fine and accurate movement of a tool in the absence of any significant amounts of torque, backlash, wobble or lateral movement. Such requirements are often met with in the fields of electrophysiological, cytological and bacteriological research, as well as in numerous other fields. Many mechanisms have been proposed for effecting a fine, closely controlled rotation free linear motion, but these mechanisms have been either too complex or have failed to provide the necessary torque and wobble-free linear motion in the absence of backlash.

It is thus a principal object of the present invention to provide an improved manipulating device.

Another object of the present invention is to provide an improved coupling arrangement.

Still another object of the present invention is to provide an improved coupling between two longitudinally aligned movable members in which the coupling force is parallel to the direction of movement.

A further object of the present invention is to provide an improved tool manipulating device for imparting a measured linear motion to the tool in the absence of any significant torque, wobble or backlash.

Still a further object of the present invention is to provide an improved tool manipulating device for imparting a fine, accurately measured, longitudinal motion to the tool in the absence of torque, wobble or backlash, the device being rugged, simple and inexpensive.

The above and other objects of the present invention will become apparent from a reading of the following description, taken in conjunction with the accompanying drawing, wherein

Figure 1 is a front elevational view, partially broken away and partially in section, of a preferred embodiment of the present invention;

Figure 2 is a sectional view taken along line 2—2 in Figure 1;

Figure 3 is a sectional view taken along line 3—3 in Figure 2; and

Figure 4 is a sectional view taken along line 4—4 in Figure 2.

In a sense, the present invention contemplates the provision of an improved tool manipulating device capable of fine, accurate adjustment and characterized by the absence of any significant torque, backlash, lateral movement or wobble, the device comprising a body member, a drive spindle having a leading flat surface; a driven spindle linearly, slidably mounted in said body member and having a trailing flat surface confronting and substantially parallel to said drive spindle leading flat surface; a coupling sphere of magnetic material disposed between said flat surfaces and in substantially point contact

2

therewith, at least one of said spindles having means for establishing a magnetic field through said spindles and coupling sphere to maintain said sphere in contact with said confronting spindle surfaces.

5 Referring now to the drawing which illustrates a preferred embodiment of the present invention, the numeral 10 generally designates a body member which includes a support frame 12 and a rearwardly directed barrel 14. The support frame 12 comprises a trailing, tubular section 16 which carries a forwardly projecting, integrally formed cradle section 18 of semi-cylindrical, external contour, terminating at its forward end with an inwardly tapering outer face 20. The inner surface of the forward portion of the cradle member 18 is of right dihedral configuration, as at 22, to define a sliding bearing surface, the bearing surface 22 extending from the forward end of the cradle 18 to a point short of the leading end of the body member tubular section 12. The body member 10 is removably supported by a bracket 24 which is carried by a suitable, universally adjustable mount of any well known construction.

The barrel member 14 has its forward end force fit into the trailing end of the body member tubular section 12 and has a smooth outer surface of circular cross section having a longitudinally extending, linear scale 26 impressed therein. The forward end of the barrel 14 is provided with a wall 28 having a smooth, bored, coaxial, circular aperture 30 formed therein defining a slide bearing, and the trailing end of the barrel member 14 is provided with a heavy wall 32 having a coaxial tapped bore 34.

A driven spindle 38 of square, transverse cross section having a flattened upper corner 40 slidably registers with the dihedral bearing surface 22. The leading end of the driven spindle 38 is provided with a forwardly projecting, axial stub 42 which carries a tool chuck or tool 44 such as a probe or the like. An axial, circular bore 46 is formed in the trailing end of the driven spindle 38 and a permanent, cylindrical bar magnet 48 formed of alnico V, a magnetic material, ceramic or other suitable permanent magnet is secured in the bore 46 and has a portion projecting rearwardly of the bore, the trailing end face 49 of the magnet 48 being flat and perpendicular to the longitudinal axis of the spindle 38.

In order to retain the driven spindle 38 in slidable registry with the dihedral bearing surface 22 with a minimum of friction, there is provided a longitudinally extending saddle member 50 including a bridge portion 52 and depending legs 54 which rest upon the upwardly directed walls of the support frame forward section 18 and is secured in position by means of bolts 56 extending through openings formed in the legs 54 and engaging corresponding tapped bores formed in the support frame section 18. A longitudinally extending, upwardly bowed leaf spring 58 nests in the saddle member 50 and carries at its midpoint an upwardly projecting pin 60 slidably registering with a vertical bore 63 formed in the saddle bridge portion 52. The front and trailing ends of the leaf spring 58 are provided with yoke portions having legs 64, the termini of which support transversely extending axles 65. Mounted on each of the axles 65 is a cylindrical roller 66 which bears upon the upper flat surface 40 of the driven spindle 38 to resiliently maintain the lower surface thereof in sliding engagement with the dihedral bearing surface 22.

65 A drive spindle 67 includes a forwardly directed, smooth surfaced, cylindrical shank 68 which slidably registers with the barrel bore 30 and a rearwardly directed, threaded shank 69 which engages the tapped bore 34. The drive spindle leading shank 68 is formed of a magnetic material such as steel or the like and terminates in a flat face 70 parallel to the trailing flat face 49 of the

magnet 48 and perpendicular to the axis of the drive spindle 67.

A thimble 71 rotatably and slidably registers with the outer surface of the barrel 14 and includes a trailing end wall 72 provided with a tapped, axial aperture 73 engaging the trailing portion of the threaded spindle shank 69. An internally and externally threaded lock nut 74 engages the portion of the threaded shank 69 projecting rearwardly of the aperture 73, the end face of the shank 69 being slotted, as at 76, to permit the axial adjustment of the spindle 69 in a well known manner. A cap 77 has an internally threaded surface which engages the external thread formed on the lock nut 74 to complete the assembly. The leading end of the outer face of the thimble 71 tapers inwardly and forwardly, as at 78, and is provided with a circumferentially extending scale 79. Both the cap 77 and the trailing portion of the thimble 71 are provided with knurled surfaces 80.

In order to effect a coupling between the drive spindle 67 and the driven spindle 38 in the absence of any significant backlash, torque, lateral movement or wobble transmission, a coupling sphere 81 having a smooth outer surface and formed of a magnetic material such as hard steel is disposed between and in point contact with the confronting flat faces 49 and 70 of the magnet 48 and the drive spindle shank 68 respectively. The sphere 81 is retained in coupling position solely by reason of the magnetic lines of force established by the magnet 48 through the sphere 81 and to the drive spindle shank 48. As a consequence of the point contact between the coupling sphere 81 and the confronting spindle flat faces 70 and 49 backlash and wobble are eliminated and there is no significant transmission of torque or lateral movement between the spindles 67 and 38.

In employing the improved manipulating device its initial position is adjusted by way of the universal mount which carries the bracket 24. Linear movement is then imparted to the tool 44 carried at the forward end of the driven spindle 38 by rotating the thimble 71 which rotates spindle 67 to advance or retard the spindle 67 along the threaded bore 34. None of this rotational movement or the resulting torque is imparted to the driven spindle 38, the only motion imparted thereto being linear and axial. The amount of linear movement of the spindle 38 may be read from the scales 26 and 79 respectively.

While there has been described and illustrated a preferred embodiment of the present invention, it is apparent that numerous alterations and omissions may be made without departing from the spirit thereof.

I claim:

1. An improved manipulating device comprising a body member, a longitudinally movable drive spindle mounted in said body member having a leading flat surface, a longitudinally movable driven spindle linearly slidably mounted in said body member and having a trailing flat surface confronting and substantially parallel to the leading flat surface of said drive spindle, a coupling sphere of magnetic material disposed between said flat surfaces, in substantially point contact therewith and laterally movable along said confronting flat surfaces, at least one of said spindles having means for establishing a magnetic field through said spindles and coupling sphere to maintain said sphere in positive contact with said confronting spindle surfaces.

2. An improved manipulating device in accordance with claim 1, wherein said magnetic means includes a permanent magnet carried by one of said spindles.

3. An improved manipulating device in accordance with claim 1, wherein one of said spindles includes an elongated member having a socket formed in an end thereof and said means includes a permanent magnet registering with said socket and having a planar free end defining one of said flat surfaces.

4. An improved manipulating device in accordance with claim 1, wherein said driven spindle carries a tool at its free end.

5. An improved manipulating device in accordance with claim 1, wherein said body member has formed at its leading end a longitudinally extending angularly shaped bearing surface and said driven spindle has a longitudinally extending dihedral surface slidably engaging said bearing surface.

15 6. An improved manipulating device in accordance with claim 5, wherein said driven spindle is of substantially square transverse cross section.

7. An improved manipulating device in accordance with claim 5, including spring means resiliently urging said spindle transversely into snug engagement with said bearing surface.

20 8. An improved manipulating device in accordance with claim 1, wherein said drive spindle is provided with a threaded shank and including a relatively stationary internally threaded element axially carried by said body member and engaging said threaded shank whereby rotation of said drive spindle effects linear movement thereof along said body members.

9. An improved manipulating device in accordance with claim 8, including means indicating the amount of linear movement of said spindles.

30 10. An improved manipulating device in accordance with claim 9, wherein said indicating means comprise a linearly extending scale marked on the outer surface of said body member, a sleeve slidably engaging said body member and secured to and rotatable with said drive spindle, said sleeve member being provided with circumferentially extending vernier marking along its leading edge.

35 11. In a device for transmitting precisely measured linear motion, a rotary- and linearly-movable drive member having a leading flat surface, a linearly movable driven member having a trailing flat surface confronting and parallel to the leading flat surface of said drive member, a coupling sphere of magnetic material disposed and laterally movable between and in point contact with said confronting flat surfaces, magnetic means maintaining said sphere in positive continuous contact with both 40 of said flat surfaces, rotary movement of the drive member producing controlled linear movement thereof and transmitting torque-, backlash- and wobble-free corresponding linear movement of the driven member.

45 12. A coupling device in accordance with claim 11, wherein said magnet means is defined by a permanent magnet carried by one of said members.

50 13. A coupling device in accordance with claim 12, wherein said permanent magnet has a planar free end defining one of said flat surfaces.
